C. H. HOWARD, OF LEWISTON, MAINE, ASSIGNOR, BY MESNE ASSIGNMENT.
TO HIMSELF AND HORACE N. JORDAN, OF SAME PLACE.

Letters Patent No. 78,453, dated June 2, 1868.

IMPROVEMENT IN WARPING-FRAME.

The Schedule referred to in these Letters Patent and making part of the same.

TO ALL WHOM IT MAY CONCERN:

Be it known that I, C. H. HOWARD, of Lewiston, in the county of Androscoggin, and State of Maine, have invented an Improvement in Beaming or Warping-Frames; and I do hereby declare that the following, taken in connection with the drawings which accompany and form part of this specification, is a description of my invention sufficient to enable those skilled in the art to practise it.

In transferring warp-yarn from the spools to yarn-beams, in what are known as "beamers" or "warpers," it is customary so effect a direct transfer, placing no mechanism between the spools and the yarn-beam, excepting the stationary guides, through and over which the yarns pass.

Great care has to be exercised in piecing the yarn whenever any breakage occurs, so as to preserve a uniform length of yarn throughout the warp, for which purpose it is necessary to stop the yarn-beam at every break. But when the beam stops suddenly the spools continue to revolve, and as they are delivering from fifty to seventy-five yards per minute, the yarns run off loosely therefrom for a half yard or more before stopping, and kink and become snarled, so that it sometimes takes hours to get them right again.

To remedy this, a balance-wheel has been applied to the rotary cylinder upon which the yarn-beam rests, so that the yarn-beam may stop gradually when a break occurs. But this is objectionable, because, if the beam continues to revolve, the broken yarns are left shorter than the others, and will not "pick up" clear, making it run off badly in the next operation, (dressing,) and consequently in the ultimate operation of weaving.

There has also been employed a take-up mechanism, consisting of a rod held up by the tension of the yarns passing under them, the weight of the rod carrying it down, and with it the slack of the yarns, when the beam is stopped by hand. But this is objectionable in that it takes the slack down into the frame where the yarns are inaccessible to the operative.

The object of my invention is to remedy the defects mentioned, by combining with the beam or frame a take-up mechanism, which shall carry the slack of the yarns up above the warper-frame, when, by reason of a breakage, the yarn-beam is suddenly stopped; and it is in the employment of a take-up roll or bar, as described hereafter, upon a beamer-frame, to take up such slack, that my invention consists.

The drawings represent a beamer-frame having my improvement embodied therewith—

A showing a plan, and

B a vertical cross-section.

a denotes the framework; b b, the stands containing the yarn-spools c, the yarn d from which passes from the spools through suitable guiding-eyes and over a guide-roll, e, to the yarn-beam f. In standards g, at opposite ends of the frame, are vertical slides, h, (sliding in suitable grooves or ways,) in the tops of which are bearings for a roll, i.

To a rod, k, connecting the lower ends of the slides h, cords l are fixed, these cords running up to and over sheaves m, and having suspended from their opposite ends a weight or weighted beam, n, which outweighs the slides and roll i, and raises the roll, when no strain or pressure is upon its upper surface. When the roll is at its lowest position, it is brought into or nearly into a horizontal plane with two guide-rolls, o, on its opposite sides, the yarns running under the guide-rolls and over the roll i, as seen at B; and when the mechanism is in operation, the strain upon the yarns holds the roll i down, (in the position seen at B,) until, by the breaking of a thread, the rotation of the yarn-beam is arrested. As the yarns run from the spool, after such arrest of the yarn-beam, the strain is taken from the roll i, and the weight n, overcoming the weight of the roll i and its frame, lifts the roll, which, by its rise, assumes the position seen by the dotted lines at B, taking up the slack between the yarn-beam and the spool-frame, as will be readily understood. By this means the yarn to be mended may be kept uniform in length with the others, and all the yarns are kept from entanglement or kinking.

More than one take-up roll, rod, or bar may be used if desirable, and the arrangement or specific method of hanging the roll, or of causing it to rise to take the slack, may be varied from that shown.

It will be obvious that with this take-up roll, if the broken ends "run by," the yarn-beam may be turned back without tangling or loosening the threads, as the roll *i* will take up slack from the yarn-beam as well as from the spools.

I claim the combination with the stationary guide, guide-rolls, or rods *o*, of the weighted rising-rod, bar, or roll, so arranged as, in its ascent, to take up the slack, substantially as set forth.

C. H. HOWARD.
